[57] CLAIM

The ornamental design for a protective foot covering, as shown and described.

DESCRIPTION

FIG. 1 is a top perspective view of the preferred foot covering;

FIG. 2 is a bottom perspective view of the foot covering of FIG. 1;

FIG. 3 is a rear elevational view of the foot covering of FIG. 1;

FIG. 4 is a side elevational view of an alternate embodiment of the foot covering of FIG. 1 having a conductive strip;

FIG. 5 is a bottom perspective view of the foot covering of FIG. 4;

FIG. 6 is a top perspective view of the foot covering of FIG. 4;

FIG. 7 is a bottom perspective view of an alternate embodiment of the foot covering of FIG. 4 in which part of the conductive strip is disposed within the foot covering; and

FIG. 8 is a top perspective view of the foot covering of FIG. 7.
